(57) **CLAIM**

The ornamental designs for an automotive wheel, as shown and described.

DESCRIPTION

FIG. 1 is an oblique view of one embodiment of the automotive wheel of the instant invention.

FIG. 2 is a front view of the embodiment of the automotive wheel shown in FIG. 1.

FIG. 3 is an oblique view of a second embodiment of the automotive wheel of the instant invention; and,

FIG. 4 is a front view of the embodiment of the automotive wheel shown in FIG. 3.

The broken line showing of environment is for illustrative purposes only and forms no part of the claimed design.
